UNITED STATES PATENT OFFICE

163,919

CONTAINER AND DISPENSER FOR BOOK MATCHES

Oscar F. Werner, San Bruno, Calif.

Application February 9, 1950, Serial No. 7,846

Term of patent 3½ years

(Cl. D48—28)

To all whom it may concern:

Be it known that I, Oscar F. Werner, a citizen of the United States of America, residing at San Bruno, in the county of San Mateo and State of California, have invented a new, original, and ornamental Design for a Container and Dispenser for Book Matches, of which the following is a specification, reference being had to the accompanying drawing, forming a part thereof.

Fig. 1 is a perspective view of a container and dispenser for book matches, showing my new design, and

Fig. 2 is a similar view and looking from the bottom of the article.

I claim:

The ornamental design for a container and dispenser for book matches, substantially as shown.

OSCAR F. WERNER.
